UNITED STATES PATENT OFFICE.

HOWARD D. MCLEOD, OF CLEVELAND HEIGHTS, OHIO.

ORE-CONCENTRATING TABLE.

1,110,070.

Specification of Letters Patent.

Patented Sept. 8, 1914.

Application filed May 18, 1910. Serial No. 561,602.

To all whom it may concern:

Be it known that I, HOWARD D. MCLEOD, a citizen of the United States, residing at Cleveland Heights, in the county of Cuyahoga and State of Ohio, have invented a certain new and useful Improvement in Ore-Concentrating Tables, of which the following is a full, clear, and exact description, reference being had to the accompanying drawings.

My invention relates to a separating device and more particularly to such a device wherein a separating platform or table is moved with a vibrating motion having a sharp reverse movement in a direction to shift the heavier and coarser material toward the end of the platform which is remote from the end of the same upon which material, to be classified, is introduced. Such a device has been successfully used in separating water from granules which are to be smelted, and it is also useful to classify material, portions of which are to be sent to the stamp mill or which, because of large size, are to be recrushed.

In the present instance I have shown and described my separating device as used in connection with a concentrating table, for the purpose of securing a preliminary separation of differently sized materials before such materials are delivered to the concentrating table, moreover, to deliver the different portions of the material, thus classified, to those positions on the concentrating table, where they can be most efficiently and effectively denuded of their values due to their deposition, subsequent action, and effect upon each other.

With the foregoing general objects in view, the invention may be defined further and also generally, as consisting of the combinations of elements embodied in the claims hereto annexed and illustrated in one embodiment in the drawings forming part hereof, wherein—

Figure 1 represents a plan view of a concentrating table constructed in accordance with my invention; Fig. 2 represents a view, partly in side elevation and partly in section, of the table shown in the preceding figure; Fig. 3 represents a rear elevation of the table shown in the preceding figures; and Fig. 4 an enlarged section detail illustrating the connection between the upper and the lower table whereby said tables are moved in reverse directions.

The invention disclosed herein comprises generally, a main table or deck having combined therewith a superposed preliminary smaller table or classifying device, by means of which the coarser or larger materials fed onto the classifying device or table, may be largely separated from the finer materials and watery slimes, and delivered onto the head of the main table; the watery slimes or fine particles being delivered to the main table in advance position with relation to the coarser materials. The material fed to the upper table or classifying device is thus treated by devices acting in series and the coarser materials and sands on the main table beneath will, by the vibration imparted thereto by the head motion be deposited so as to travel from the head of the table across and beneath the slimes, collecting therefrom whatever fine or floating values may be therein and carrying such values by entrapping them among such coarse grains to the discharge end of the table, and thus effect their recovery.

Describing the parts shown herein by reference characters, 1 designates the classifying device, which is used for roughing out or preliminarily classifying the material supplied therefrom to the main table. This device, as shown, is a deck or table of flat surface which lies substantially in a single plane, which is inclined with respect to the horizontal. This table is considerably smaller than the main deck or table therebeneath and is supported so that it occupies a position immediately above the depressed head end of the main table. It is preferably supported above the main table receiving horizontal vibration therefrom, but, by the construction to be described, is vibrated so that the sharp reverse is in a direction the reverse of that of the latter table. As a means for supporting the classifier, I provide, in this case, a cross bar 3 which is supported at the upper ends of a pair of flat springs 4, the lower ends of the springs being supported from any suitable portion of the foundations or floor on which table rests. This cross bar 3 is shown as connected to the head 6 of the classifying table 1, by means of bolts 7 extending through the bar and through the head. The opposite end or tail of the classifying table 1 is supported above the table 2 through a lever 8, which is pivoted intermediate of its ends to a bracket 9, as shown at 10. This lever

is provided with a series of notches 11 at its opposite ends, each series of notches being adapted to receive projections 12 and 13 carried respectively by a connecting member 14 secured to the upper table and a connecting member 15 secured to the lower or main table. The members 14 and 15 may be made of strap iron.

The springs 4, which are connected to the head of the table 1, and the springs (to be described) which are connected to the main table, serve to keep the projections 12 and 13 firmly in place within their respective notches, the notches affording an adjustable connection between the tables and the lever 8. A suitable feed hopper 16 is supported from the head 6 of the table 1, and said table is provided with a series of riffles 17 extending continuously from the head of the 20 table to the tail.

The table 2 is provided with riffles 19, shown as extending the full length thereof, the head of the table being inclined, as shown at 20. The main table is supported by two longitudinal series of legs, each of which is pivotally connected at its upper end to the bottom of the table, as shown at 22. The legs which support the discharge side of the table have their lower ends pivotally supported in cups 23 carried by the horizontally extending arms 24 of a series of bell crank levers. The vertical arms 25 of the levers are connected to a common link 26. This link may be adjusted to vary the inclination of the table 2, through its bell crank connections with the legs 21, by means of a bolt 27 extending through a suitable plate 28 and having on its end a nut 29 provided with arms 30, by means of which it may be rotated. Each leg 21 is itself adjustable, comprising two sections connected by a turn-buckle 21^a. Suitable transverse braces 31 may be employed to prevent the racking of the legs 21.

At the head of the main table is provided the "head motion" 32, which may be of any approved construction, and which is shown as connected to the main table by means of a pair of straps 33, each having its rear end connected to a bolt 34 between a pair of adjusting nuts 35 thereon, said bolts in turn being connected to a cross bar 36 projecting from the bottom of the main table. The straps 33 are connected at their front ends to a nut 37 which is mounted upon a bolt 38, the bolt being supported in a frame 39, the lower end of which is pivotally supported at 40, the frame being connected to the head motion 32. A spring 41 connects the lower end of a rod 42 to a stationary part of the bed, the upper end of the rod being connected to the table 2. The spring tends to maintain the table 2 at the rear end of its path of vibration, and, together with the spring 4, to maintain the

projections 12 and 13 in engagement with the notches in the lever 8.

In operation, the table 2 is operated by the head motion and this motion transmitted, though in the reverse direction, by 70 the lever 8 to the table 1. Material which is fed onto the table 1 is preliminarily classified and discharged onto the head of the main table, adjacent to the feed side thereof, the slimes passing over the rear 75 edge 1^a of said table and the granular material passing over the tail 1^b of said table. Under the vibration imparted to the main table, the granular material follows the direction of the arrows A and the slimy water 80 travels in the direction of the arrows B. The sands and heavier material travel across and beneath the slimes and slimy water and trap therefrom practically all of the values which would otherwise escape. 85 The provision of the riffles on the main deck or table 2 maintains the stratification, so that when values of different specific gravity occur they may be caught in different receptacles. The classification or separating 90 table need not necessarily be located in close proximity to the concentrating table but may be at a point quite remote therefrom, if desired, as, for instance, in the upper part of the building in which the concentrating 95 apparatus is located and the classified material from the separating device will be delivered to the concentrator by suitable conveyors. However, such conveyors will be so arranged as to deliver classified material 100 in the same relative position as would be the case when the two devices are arranged, as here shown and described.

In using the terms separating platform, separating table, etc., I use them in their 105 broad meaning and include all such devices as will accomplish their function.

Having thus described my invention, what I claim is:—

1. The combination, with an ore classifying table, of a feeder therefor comprising a plane table mounted above and independently of said main table and provided with longitudinal riffles, the riffles of said tables being substantially parallel and said tables 110 being inclined transversely of their riffles in opposite directions, the lower side of said feeder table being above and adjacent to the higher side of said main table, means for imparting to said main table a horizontal 115 differential vibration in the direction of its riffles, and means for imparting to said feeder table a horizontal, differential vibration in the direction of its riffles, such differentials being in opposite directions. 120

2. The combination, with an ore classifying table having a general diagonal inclination and means for reciprocating the same in a direction oblique to such line of inclination, of a feeder therefor comprising a sec- 130

ond table supported thereabove and having a general diagonal inclination opposite to that of the main table, means for imparting to said feeder table a horizontal differential vibration opposite to and independent of the motion of said main table, the direction of movement of said main table and feeder table being substantially parallel, means for delivering mixed granular and slimy material to said feeder table, and means for adjusting the angle of said feeder table independently of said main table whereby the coarser and more granular material will be delivered to said main table adjacent its head end, and the slimes adjacent one of the sides thereof.

3. The combination, with an ore-classifying table having longitudinal riffles and means for imparting to said table a differential, horizontal vibration in the direction of said riffles, of a feeder therefor comprising a plane table supported above said main table and also having longitudinal riffles substantially parallel to those of the main table, means for imparting thereto a horizontal, differential, vibration in a direction parallel to its riffles and opposite to the vibration of said main table, and means for supplying granular ore and water to that part of the feeder table which is nearest the discharge side of said main table, the direction of the differential of feeder table vibrations being such as to discharge concentrate and liquid at points of said main table farthest from the discharge side for such concentrate and liquid respectively.

4. The combination, with an ore classifying table having a slope in two directions and means for reciprocating the same longitudinally whereby granular material may be delivered over one of its end edges and watery material over one of its side edges, of a feeder table also having a slope in two directions and supported above said main table, the slope of said feeder table being opposite to that of the main table, means for delivering mixed granular and pulverized material together with water to the lower end of said feeder table, and means for imparting to said feeder table a reciprocation independent of and opposite to the reciprocation of said main table, the direction of motion of said feeder table being substantially parallel to that of the main table, and said feeder table having longitudinal riffles substantially parallel to the direction of its motion, whereby the more granular of said material will be delivered to said main table at the portion farthest removed from the discharge end for said granular material and said watery material may be delivered to said main table at a point farthest removed from the discharge portion for such material.

5. The combination, with an ore classifying

table having a general diagonal inclination and means for reciprocating the same in a direction oblique to the line of inclination, of a feeder therefor comprising a second table supported thereabove and having a general inclination opposite to that of the main table, said second table having corrugations or riffles substantially parallel with the direction of movement of said main table, said feeder table being disposed over the lower end and higher side of the main table and having its discharging end presented toward the lower end of said main table, means for delivering mixed material together with water to the lower end of said feeder table, and means for imparting to said feeder table a differential reciprocatory movement substantially parallel to the direction of its corrugations or riffles, such reciprocatory movement being opposite to and independent of that of the main table, whereby the coarser and heavier material will be delivered to the main table at the portion farthest removed from the discharge end for concentrates, and the finer and lighter material at the portion farthest from the tailings discharge.

6. The combination, with an ore classifying table having longitudinal corrugations and supported in an inclined position, the line of greatest inclination making an oblique angle with the direction of said corrugations, and means for reciprocating said table in a direction substantially parallel with said riffles, of a feeder therefor comprising a second table supported thereabove and having an inclination opposite to that of said main table, said feeder table having a discharge end above the end of the main table opposite to its discharge end and a discharge side above the side of the main table opposite to its discharge side, said feeder table having longitudinal corrugations or riffles intersecting its discharge portion, means for reciprocating said feeder table independently of said main table in a direction substantially parallel to its riffles or corrugations, and means for delivering ore to said feeder table at a point removed from its discharge portion.

7. The combination, with a differentially reciprocating table adapted to cause heavy material to travel longitudinally and lighter material to travel transversely, of a differentially reciprocable plane table overlying said first table and having unobstructed discharge sides for lighter and heavier material, the discharge side for heavier material being disposed above the opposite end of said first table from its discharge end for such material and the discharge side of the second table for lighter material being disposed above the opposite side of the main table from its discharge side for such lighter material, said second table being inclined down-

wardly in the direction of its discharge side for lighter material, and means for imparting to said second table a differential reciprocation opposite to and independent of that of the main table, whereby material of whatever nature on said second table will be caused to progress in the opposite direction from that of similar material on said main table.

- 10 8. The combination, with an ore classifying table having a slope in two directions and riffles running in one of those directions, of a feeder table mounted above said first table and also having a slope in two directions, the direction of slope of said feeder table being in each case opposite to the direc-

tion of slope of said first table, and said feeder table also having riffles running substantially parallel to the riffles of said first table, said feeder table being located substantially over the receiving side of said first table, and means for differentially actuating said tables in opposite directions substantially parallel to the direction of their riffles.

20 In testimony whereof, I hereunto affix my signature in the presence of two witnesses.
